ACCESSORY TANK FOR A BICYCLE

Viktor Schreckengost, Cleveland Heights, Ohio, assignor to The Murray Ohio Manufacturing Company, Nashville, Tenn., a corporation of Ohio

Application December 2, 1957, Serial No. 48,746

Term of patent 14 years

(Cl. D90—1)

Fig. 1

Fig. 2

FIG. 4

Fig. 1 is a right side elevational view of an accessory tank for a bicycle, showing my new design, the dot-dash representation being for illustrative purposes only;

Fig. 2 is an enlarged top plan view thereof;

Fig. 3 is an enlarged end view of Fig. 2; and

Fig. 4 is a perspective view thereof taken from a point at the left side and somewhat toward the front.

I claim:

The ornamental design for an accessory tank for a bicycle, substantially as shown and described.
